RAYMOND T. PIERCE, OF WILKINSBURG, PENNSYLVANIA, ASSIGNEE TO WESTINGHOUSE ELECTRIC & MANUFACTURING COMPANY, A CORPORATION OF PENNSYLVANIA.

THERMAL RELAY.

Application filed August 18, 1921. Serial No. 493,279.

My invention relates to relays and particularly to thermal relays.

One object of my invention is to provide a thermal relay that shall protect an electric circuit in accordance with the temperature obtaining within a predetermined portion of the circuit.

Another object of my invention is to provide a relay, of the above-indicated character, whereby an auxiliary control circuit shall be controlled and energized in accordance with the temperature of a predetermined portion of the circuit.

A further object of my invention is to provide a relay, of the above-indicated character, that embodies a fluid conductor to be heated in accordance with a predetermined portion of the circuit serving to control the auxiliary control circuit in accordance with the temperature of that portion.

A further object of my invention is to provide a relay of the above-indicated character that shall be simple and economical in construction and effective and reliable in its operation.

In my co-pending application, Serial No. 493,278, filed Aug. 18, 1921, I disclose a direct-trip system wherein a thermal relay of the mercury type is employed to control the energization of the trip coil from the circuit to be protected. The mercury relay illustrated therein comprises a capillary tube containing a column of mercury that is so connected to the circuit as to be heated in accordance with the temperature of the apparatus therein. Upon attaining a predetermined temperature, the mercury column is broken or separated.

In practicing my present invention, I provide a relay that operates upon the same principle. The relay comprises a tubular container of insulating material within which is disposed a column of mercury. Terminal members that are sealed into the tube at the respective ends thereof serve as connecting means whereby the column of mercury may be connected to an electric circuit. The relay is designed to have a temperature characteristic corresponding to that of a predetermined portion of the circuit and, when a predetermined temperature is attained therein, engagement is effected between the column of mercury and an auxiliary terminal member that is normally not engaged thereby, to complete a control circuit which is connected to

such auxiliary terminal member. Upon the completion of such circuit, the desired operation for the protection of the apparatus is effected.

Figure 1 of the accompanying drawings is a diagrammatic view of an electrical circuit including a relay embodying my invention, and

Fig. 2 is a diagrammatic view of a circuit including a modified form of the relay that is illustrated in Fig. 1.

In Fig. 1, a translating device, such as a motor 1, receives energy from a supply circuit 2 through a circuit interrupter 3. Effective protection for the motor 1 is provided by means of a thermal relay 4 that is energized from the circuit through a current transformer 5. The thermal relay 4 is designed to have a temperature characteristic corresponding directly to that of the motor 1. When a predetermined dangerous temperature is attained in the motor and, consequently, in the thermal relay 4, the relay effects the actuation of the interrupter 3 by completing a circuit for energizing the trip coil 6 of the interrupter.

The relay 4 comprises a tubular member 7 of insulating material, such as glass or quartz, within which is disposed a body of mercury 8 and two terminal members 9 and 10 that are sealed into the tube to normally engage the body of mercury 8. The tubular member 7 is further provided with an auxiliary chamber 11 that communicates therewith and within which is disposed a terminal member 12 that normally does not engage the mercury within the chamber. The terminal member 12 is connected to one terminal of the trip coil through a source 13 of direct-current electromotive force. A complementary terminal member 14 is disposed within the tube 7 intermediate the terminal members 9 and 10 and is connected to the other terminal of the trip coil 6.

The relay 4 may be provided with suitable lagging or may be disposed in a suitable casting to prevent undue dissipation of heat therefrom to cause the same to have a temperature characteristic corresponding to the temperature characteristic of the motor 1. When the temperature within the motor 1 and, consequently, within the relay 4 attains a predetermined dangerous value, a portion of the mercury within the tubular member 7 will be vaporized and enter the chamber 11.

When a spark is produced by the mercury heating to a predetermined degree and separating within the tube 7, the circuit of the trip coil will be completed between the auxiliary contact members 12 and 14 and the trip coil will be energized to actuate the interrupter 3 to disconnect the motor from the circuit 2.

In Fig. 2 is illustrated a modified form of 10 the relay shown in Fig. 1. In the relay that is illustrated in Fig. 2, the chamber 11 is disposed at one end of the tube 7, and only one auxiliary terminal member 12 is employed. Energy for the trip coil is derived from the 15 circuit through a potential transformer 15.

When the temperature characteristics of the circuit are such that the relay 4 is caused to operate, the mercury 8 within the tube 7 will rise to effect engagement between the 20 contact members 9 and 12, whereupon the circuit of the trip coil 6 will be completed and the interrupter actuated to disconnect the motor from the circuit.

It will be observed that, in the system employing a direct-current control circuit, the 25

presence of mercury vapor and an arc is sufficient to complete the circuit of the trip coil, while, in the system employing an alternating-current control circuit, engagement of the contact members by the mercury is necessary. 30

Although I have illustrated preferred forms of relays embodying my invention, various modifications may be made therein within the spirit and scope of the invention, 35 as set forth in the appended claim.

I claim as my invention:—

A thermal relay comprising a column of 40 electric-conducting liquid, electrodes in contact therewith adapted to pass a current therethrough, means whereby said column is ruptured responsive to an abnormal current value therein, an additional electrode normally out of contact with said liquid, and means responsive to the rupture of said column for completing a circuit through said 45 additional electrode.

In testimony whereof, I have hereunto subscribed my name this 8th day of August 1921.

RAYMOND T. PIERCE.
